[57] CLAIM

The ornamental design for a portion of a shoe outsole, as shown and described.

DESCRIPTION

FIG. 1 is a bottom plan view of a portion of a shoe outsole showing my new design;
FIG. 2 is a cross sectional view taken along line 2—2 of FIG. 1;

FIG. 3 is a cross sectional view taken along line 3—3 of FIG. 1;
FIG. 4 is a perspective view of the portion of a shoe outsole of FIG. 1;
FIG. 5 is an enlarged view of the sectional of FIG. 2; and,
FIG. 6 is an enlarged view of the sectional of FIG. 3.

The broken line showing of a region in the arch outsole, the four oval shapes in the heel area and sole periphery is for illustrative purposes and forms no part of the claimed design.
